MACHINE FOR MARKING LETTERS
AND THE LIKEAugust Ielfield, Silver Creek, N. Y., assignor of
one-half to John W. Slack, Silver Creek, N. Y.

Application April 24, 1946, Serial No. 664,572

6 Claims. (Cl. 101—235)

1

This invention relates to a machine for marking envelopes, cards, collapsed cartons, and similar matter for the purpose of cancelling postage or post marks thereon and also for imprinting information on flattened paper bags or the like containing seed or other merchandise all of which matter, for convenience of description, will be hereinafter referred to under the general term of "letters" or "printing matter."

A further object of this invention is to provide an improved frictional coupling or clutch for transmitting motion from the driving wheel to the printing wheel and enable the frictional engagement of this clutch to be readily increased so as to restore the driving effect of the clutch when the same becomes worn and tends to permit the printing wheel to slip on the driving wheel, thereby insuring proper timing or locating of the impression on the letter which is being marked instead of causing the impression on the letter to be thrown back thereon in an improper position.

An additional object of this invention is to provide means whereby the printing wheel may be so adjusted relative to the trip mechanism which controls the starting of the printing wheel that the printing or impression on the letters may be located at different distances from the front or advancing edge thereof when it is desired to produce a mark on the letters other than that usually placed thereon for cancelling postage, such for example as marking envelopes for use in distributing seeds which require certain information on the envelopes as to the age of the seed and the fertility of the same.

This invention also comprises certain improvements in details of construction over the disclosure in United States Patent No. 1,703,148, as will presently appear.

With these objects in view, this invention consists generally in the improved organization which is shown in the accompanying drawings.

In these drawings

Figure 1 is a top plan view of a marking machine embodying a preferred organization of this invention.

Figure 2 is a bottom plan view of the same.

Figures 3 and 4 are vertical longitudinal sections of this machine taken on the correspondingly numbered lines in Figure 1 and looking in the direction of the arrows associated with these lines.

Figure 5 is a vertical transverse section of the machine taken on line 5—5, Figure 1.

Figure 6 is a fragmentary horizontal section,

5 on enlarged scale, taken on line 6—6, Figure 5, and showing the printing wheel in the position which it occupies when its control or trip mechanism has been released by the matter which is being marked and permits the printing wheel to rotate for producing an impression on this matter.

Figure 7 is a similar view showing the position of the parts in which the trip mechanism holds 10 the printing wheel at rest preparatory to being released by a letter which is to be marked.

Figure 8 is a similar view of some of the parts shown in Figures 6 and 7 but in a position in 15 which the printing wheel has completed its printing operation and has been arrested, but the letter or printing matter has not yet cleared the printing wheel during the forward movement of the letter.

Figure 9 is a fragmentary vertical transverse 20 section, on an enlarged scale, taken generally on line 9—9, Figure 1.

Figure 10 is a vertical transverse section taken 25 on line 10—10, Figure 11.

Figure 11 is a horizontal section taken on line 23 11—11, Figure 9.

Figure 12 is a perspective view of the friction 30 block or shoe forming part of the coupling or clutch for frictionally connecting the printing wheel with its driving means.

Figure 13 is a fragmentary vertical cross section taken on line 13—13, Figure 1.

Figure 14 is a horizontal section, on an enlarged 35 scale, taken on line 14—14, Figure 5.

Figure 15 is a fragmentary horizontal section, 40 on an enlarged scale, similar to Figures 6 and 7 and showing a modified form of the means for supporting a plurality of backing-up rollers as a unit on a yoke or hanger.

Figure 16 is a vertical longitudinal section 45 taken on line 16—16, Figure 15.

In the following description, similar characters of reference indicate like parts in the several figures of the drawings:

Although the frame on which the several working parts of this machine may be variously constructed the same, as shown in the drawings, 45 preferably comprises a main plate 20 of cast metal, a horizontal table 21 of sheet metal secured to the upper side of this plate, vertical flanges 22 depending from the edges of the table and upright legs 23 projecting downwardly from said flanges and adapted to rest on a work bench or other support.

The letters 24 or other like matter to be marked 50 are fed over the top of the table from a rear sup-

ply section 25 thereof, past a printing mechanism which marks the letter and to a receiving section 26 upon which the letters are stacked after being marked.

Lengthwise above the feed table is arranged a guide wall having a rear section 27 against which the pile or stack of unmarked letters is pressed transversely by a feeding follower 28, and a front section 29 from which the letters are pushed away transversely by a rotary stacking wheel 30.

The feeding follower 28 is constantly pressed crosswise of the table and toward the rear guide wall section 27 by means which include an upright rock shaft 31 journaled in a bearing on the adjacent part of the frame and connected at its upper end with this follower, a rock arm 32 secured to the lower end of the rock shaft 31, a spring 33 connected at one end with this rock arm, an adjusting screw 34 connected with the opposite end of this spring and passing through the adjacent part of the frame flange 22, and a screw nut 35 applied to the outer end of the screw 34 and engaging the outer side of the frame flange, as shown in Figures 1, 2, and 4.

Above the supply section of the table and extending across the same is a transverse retaining wall 36 the inner end of which is spaced from the longitudinal guide wall section 27 by a feed passage or a gap or throat 37 through which the letters move from the supply section of the table to the mechanisms which subsequently mark the letters and restack the same.

The letters are fed successively forwardly from the inner side of the supply stack on the rear section 25 of the table by means which are constructed as follows:

The numeral 38 represents a rear feed roll which has the inner part of its periphery projecting through an opening 39 in the rear section 27 of the longitudinal guide wall and adapted to engage successively with the rear side of the foremost letters of the stack on the supply section of the table, this roller being turned so that its front side moves forwardly and thereby causes the letters to be moved forwardly through the separating throat or gap 37. This rear feed roll is journaled on an upright pin or arbor 40 which is mounted in a fixed position on the adjacent part of the frame.

Immediately in front of the rear feed roller is arranged a front feed roll 41 which has its inner side also projecting through the opening 39 in the rear guide wall section and adapted to engage with the rear side of each letter after the same passes through the throat 37 and thereby aid in continuing the forward movement of each letter from the supply stack to the marking mechanism and the restacking mechanism. This front feed roll is journaled on an upright pin or arbor 42 which is fixedly mounted on the adjacent part of the frame and is rotated so that its inner part moves forwardly relative to the table.

The rear and front feed rolls 38, 41 are operatively connected so that the rear feed roll turns somewhat slower than the front feed roll, this being preferably accompanied by means of a belt 43 which passes around a small driving pulley 44 on the upper end of the front feed roll and a large driven pulley 45 mounted on the upper end of the rear feed roll, as shown in Figures 1 and 3. The inner side of the rear part of the feed belt 43 also preferably engages successively with the back of the foremost letter of the supply stack and thus aids in feeding the same

forwardly from the supply stack toward the marking and restacking mechanisms.

Rotation of the front feed roller is effected by means of a feed or propelling belt 46 which has an operative stretch 47 extending lengthwise from the receiving section of the feed table, past the marking mechanism and to the receiving section of this table and having a rear turn which passes around a pulley 48 on the lower part of the front feed roller 41, a front turn which passes around a pulley 49 connected with the stacker, and an intermediate turn which passes through a main driving pulley 50. The last mentioned pulley is secured to the upper end of a driving shaft 51 which is journaled in a bearing on the adjacent part of the frame and may be turned either manually or by power, but as shown in Figures 1 and 2 rotation of this shaft is effected by means of a crank 52 secured to the upper end of this shaft and provided with a handle 53 for rotating this shaft by hand power. The stacker 30 and its pulley 49 are secured to the upper end of the stacker shaft 54 which is journaled in a bearing on the adjacent part of the main frame.

Any slack in this driving belt may be taken up by means of a take-up roller 55 which engages with this belt between the front feed roll pulley 48 and the driving pulley 50 and adjustably connected with the main frame by means of a bracket 56 arranged above the table and provided with a pivot pin 57 upon which the take-up roller is mounted and a slot 58 which receives an adjusting screw 59 secured to the main frame.

Means are provided for preventing more than one letter at a time from being fed off from the supply stack to the printing mechanism which means in their preferred form are constructed as follows:

The front feed roller 41 is of a diameter equal to the diameter of the pulley 48 and the thickness of the feed belt 46 and these members are separated vertically from each other adjacent to the path of the letters by an intervening gap 60, as shown in Figure 13. Opposite to this gap the front side of the letters are engaged by a separating roller or wheel 61 which rotates in a direction opposite to the opposing surfaces of the feed belt and the front feeding roller 41 and pulley 48 whereby all letters in rear of the foremost letter on the supply stack are held back and only the foremost letter is permitted to move from the supply stack to the printing mechanism.

This separating roller is mounted on the upper end of a vertical shaft 62 which extends downwardly through a slot 63 in the table and has its lower part journaled on a rock arm 64 which is pivoted by a pin 65 on the main frame so that it can swing horizontally.

Motion is transmitted from the stacker shaft 54 into the separator shaft 62 by a transmission belt 66 which passes around a small pulley 67 secured to the lower end of the stacker shaft and a large pulley 68 secured to the lower end of the separator shaft, as shown in Figures 2, 3, 4 and 13. This belt is preferably constructed of spring wire which is coiled helically, thereby not only forming a driving connection between the pulleys 67 and 68 but also retaining this belt constantly in a tight condition so as to reliably transmit motion from the small pulley 67 to the large pulley 68 and also permit the separator wheel or roller 61 to move horizontally the required extent in order to adapt it to the varying thicknesses of letters or other like matter passing between the separator wheel or roller 61 and the adjacent

surface of the feed belt and the front feeding roller 41 without requiring any take-up or other means for maintaining this belt in a proper working condition.

Means are provided for limiting the movement of the separator wheel 61 toward those parts of the feed belt and the front feeding roller 48 adjacent to the gap 69, and thereby prevent the periphery of the separating wheel from entering this gap and insuring the maintenance of the spacing between these members so that the thinnest letters will be effectively gripped between them and prevent more than one letter at a time from being fed from the supply stack to the printing mechanism. The preferred means for effecting this adjustment includes an adjusting rod 69 connected at one end with a sleeve 70 surrounding the upper part of the separator shaft 62 and passing at its opposite end through a post 71 secured to the adjacent part of the feed table an adjusting screw nut 72 working on a threaded portion of the rod 69 and engaging with the outer side of the post 71 and a clamping nut 73 also working on the threaded portion of this rod and engaging with the adjusting nut 72, as shown in Figures 1 and 13.

The printing mechanism whereby the letters or other like matter are impressed with a cancelling mark or other printing is arranged between the supply section 25 and the receiving section 26 of the feed table and in its preferred form this printing mechanism is constructed as follows.

The numeral 74 represents a printing wheel which turns about a vertical axis and has its periphery arranged opposite the outer side of the longitudinal stretch 47 of the feed belt so that the letters passing forwardly between this printing wheel and the feed belt will receive an impression on the front side end corresponding to the character of the type, die or other impression member mounted on the printing wheel. As shown in the drawings this printing wheel is provided on one part of its periphery with wave-like printing ribs 75 which produce correspondingly shaped lines on the letters and another part of the periphery of this printing wheel is provided with a removable die 76 the face of which may be provided with type or the like for impressing dates or other information on the letters.

This printing wheel is at rest and held against rotation when no letter is passing forwardly between the same and the feed belt, but when the letter, while being fed forward reaches this printing wheel the latter is released and permitted to rotate its type face in engagement with the letter during the forward movement of the same and produces an impression of the type face on the letter. The means for thus holding the printing wheel against rotation when no letter is present between the same and the feed belt but is released to permit the printing wheel to produce an impression on the letter are preferably constructed as follows:

The numeral 77 represents the tubular hub of a driving wheel and 78 the lower circular driving rim or disk of this wheel. The hub of the driving wheel engages with the cylindrical bore of the printing wheel 74 and the lower driving rim of the same bears against the lower end of the printing wheel through the medium of an interposed fiber washer 79. This driving wheel rotates on an upright arbor 80 secured on its lower end to the main frame and is rotated constantly by engagement of its lower rim or disk 78 with the

adjacent lower edge portion of the feed belt, which moves forwardly at this place.

Friction coupling or clutch means are provided whereby the printing wheel is rotated by the driving wheel when the printing wheel is free to rotate, but when the printing wheel is held against rotation, the driving wheel rotates independently of the printing wheel. This friction coupling or clutch embodies a feature of the present invention and is constructed as follows:

Referring to Figures 5, 10, 11 and 12, the numeral 81 represents a friction block or coupling shoe made of fibre or other suitable material having a high friction quality and bearing with its inner side against the periphery of the tubular hub 77 of the driving wheel. This coupling block is arranged in a longitudinal groove 82 formed in the bore of the printing wheel and is compelled to turn with this wheel but is capable of moving toward the hub of the driving wheel in order to take up wear on the coupling block. In order to guide this coupling block without fitting the same tightly in the groove 82 and permit it to move freely radially relative to the driving wheel and printing wheel, guiding means are provided which preferably consist of two retaining or guide pins 83, 83 secured to the upper and lower parts of the printing wheel and projecting radially inward at opposite ends of the groove 82 and into outwardly opening longitudinal notches 84 formed at opposite ends of the coupling block. Spring means are provided for yieldingly holding the coupling block against the hub of the driving wheel which means consist preferably of a leaf spring 85 with its central part toward the back of the groove 82 while its opposite ends engage with inwardly facing undercut seats, shoulders or hooks 86 formed on the outer side of the opposite ends of the coupling block. In order to permit of adjusting the tension of this spring so as to produce the desired pressure of the coupling block against the driving hub 77, means are provided which preferably consist of an adjusting screw 87 working in a threaded radial opening in the printing wheel and engaging its inner end with the central bowed part of this spring while its outer end is provided with a notch which is accessible from the outer side of the printing wheel to permit a screw driver to be used for turning this screw and adjusting the tension of this spring accordingly.

When the printing wheel is free, the same is coupled by means of this frictional clutch or coupling with the driving wheel so that the same turn together and cause the printing wheel to produce an impression of its die or impression surface against the letter which is passing between the printing wheel, driving wheels and the feed belt, but when the rotation of the printing wheel is arrested the driving wheel continues to rotate independently of the printing wheel at which time the driving hub 77 slips on the friction coupling block. When the coupling block becomes worn to such an extent that the frictional engagement of the same with the driving hub is not strong enough to cause the printing wheel to be immediately turned with the driving wheel upon release of the printing wheel, then a slight tightening turn of the adjusting screw 87 causes the tension on the spring 85 to be increased so that a sufficiently strong grip of the coupling block on the driving hub is produced to insure prompt starting of the printing wheel with the driving wheel when the printing wheel is released.

By this means it is possible to begin the marking or cancelling operation on the face of a letter immediately at the front or advancing edge of the same, instead of delaying this operation and causing the printing to begin at a distance from the front edge of the letters as would be the case if a slippage of the printing wheel on the driving wheel would occur before the printing wheel is picked up by the driving wheel.

By engaging at opposite ends of the tension spring 85 with undercut or hook shaped shoulders at opposite ends of the friction block this spring is securely held in position on the coupling block and prevented from shifting lengthwise and thereby causing the pressure of the adjusting screw 87 against the spring 85 to be more effectively transmitted to the driving hub.

By means of the adjusting screw 87 it is possible to restore the proper tension of the spring 85 in case the same becomes weak and thus insure placing the mark exactly in the proper place on the letter instead of permitting the impression to be thrown back on the letter and possibly missing the postage stamp in the usual position at the upper right hand corner of the envelope or the like as would be the case if the clutch or coupling were permitted to slip.

Controlling means are provided whereby the printing wheel is held at rest when no letter is passing between the same and the feed belt but which permit the printing wheel to make one complete rotation and impress its printing face on a letter when the front edge of the latter reaches the printing wheel and is fed forwardly past the same. The preferred organization of the control mechanism is constructed as follows:

The numeral 88 represents a supporting disk provided with a central opening which receives the upper part of the arbor 80 and secured to the upper end of the printing wheel so as to be compelled to turn therewith. The periphery or rim of this supporting disk is of cylindrical form and concentric with the cylindrical periphery of the driving disk 78 of the driving wheel and of the same diameter. These disks 78 and 88 are coaxial with the arbor 80 and adapted to engage either with the opposing face of the feed belt or with the letter passing between this belt and the printing roller so that the latter is rotated when the same is free to turn.

At the end of each rotation the printing wheel and the parts mounted thereon are stopped and held against forward rotation by means of a trip lever 89 which is pivoted at its rear end by means of a pin 90 on the upper side of the supporting disk 88 and provided with a movable stop 91, having preferably the form of a roller, and adapted to engage with a stationary stop 92 mounted on a bracket 93 forming part of the main frame and also preferably having the form of a roller. This trip lever is yieldingly turned outwardly so that at the end of each bodily rotation it will engage its movable stop 91 with the fixed stop 92, this being accomplished by means of a spring 94 connecting the heel of the trip lever with the adjacent part of the supporting disk 88 as shown in Figures 6, 7 and 9. The outward movement of this trip lever under the pull of the spring 94 is limited by means of a stop pin 95 projecting upwardly from the supporting disk 88 and engaged by the outer side of the trip lever, as shown in Figure 7.

On the front end of the trip lever is pivoted a trip finger 96 by means of a pin 97. When the printing wheel is at rest, this trip finger is moved

outwardly and into a position across the path of the letters as they approach the printing wheel, this being accomplished by means of a spring 98 interposed between the trip finger and the adjacent part of the trip lever on one side of the pivot pin 97. The outward movement of the trip finger under the action of the spring 98 is limited by engagement of a stop 99 on the trip finger on the opposite side of the pin 97 with a stop 100 on the adjacent part of the trip lever, as shown in Figures 6 and 7.

When no letter is present between the printing wheel and the feed belt the printing wheel is at rest, and the same is locked against forward movement and the trip finger projects outwardly across the path of the letters, as shown in Figure 7. When a letter is fed forwardly its front edge engages with the trip finger and moves the same and the trip lever inwardly a sufficient extent to disengage the movable stop 91 of the trip lever from the fixed stop 92 on the frame bracket 93, thereby releasing the printing wheel and causing the same to be turned forwardly by frictional engagement of the driving wheel disk 78 and the supporting disk 88 with the face of the letter which is being fed so that an impression of the printing wheel is produced on the letter for cancelling or marking the same.

After the printing wheel has effected the initial part of its rotation and the trip finger is disengaged from the letter as shown in Figure 6, and the trip lever is thrown outwardly by the spring 94 so that the movable stop 91 on the trip lever is intercepted by the fixed stop 92 on the frame bracket 93, thereby arresting the further forward rotation of the printing wheel notwithstanding that the driving wheel continues to rotate and the feed belt moves forwardly and the letter which has been marked is moved forwardly independently of the printing wheel. If the tail end or rear edge of the letter has not yet passed the trip finger at the time that the trip lever arrests the forward movement of the printing wheel, then the trip finger will engage with the face of the forwardly moving letter and be thereby pushed backwardly against the tension of its spring 98 and held out of the path of the letters as shown in Figure 8.

As soon however as the rear end of the respective letter, during its forward movement, has cleared the trip finger the latter is instantly turned outwardly by its spring 98 into a position in which the finger projects across the path of the next following letter and thereby is again in a position to release the printing wheel and begin the next cycle of the operations of printing a mark on a letter.

Supplemental means are provided for producing an additional frictional coupling effect between the printing wheel and the driving wheel by pressing the printing wheel downwardly against the washer 79 on the upper side of the driving wheel disk 78, this being accomplished as follows:

The numeral 101 represents a pressure collar which surrounds the arbor 80 and bears with its underside against the upper side of the supporting disk 88, as shown in Figures 5 and 10. This collar is free to move lengthwise on the arbor 80 but is held against turning thereon by means of a key pin 102 extending through this collar and a vertical slot 103 in this arbor, as shown in Figures 9 and 10. A downward pressure on the collar is exerted by spring means which pressure is transmitted by the supporting disk 88

and printing wheel to the washer 79 on top of the driving disk 78. Pressure means for this purpose preferably comprise a helical spring 104 arranged within a pocket 105 formed in the upper end of the arbor, said spring bearing with its lower end against the key pin 102 while its upper end bears against an adjusting screw 106 working in the threaded upper part of the arbor and held in its adjusted position by means of a lock nut 107. By tightening the screw 106 more or less the frictional engagement of the lower end of the printing wheel with the washer 79 on the driving disk 78 may be adjusted to suit requirements. This adjustment can be effected while the machine is in operation by means of a screw driver engaging a nick in the upper end of the adjusting screw 106, thereby permitting of putting the machine quickly in the best working condition.

When marking letters bearing postage adjacent to the advancing edge and front side thereof the timing or controlling of the printing mechanism relative to the feed mechanism is so adjusted that the impressing of the letter by means of the printing wheel begins at the front end or edge of the letter. When however it is desired to produce a mark on the face of a letter or other matter that should begin at a distance from the front edge of the same, as for example, when printing information on the face of an envelope or carton as to its content such as the germinating period of seed in the envelope in accordance with legal requirements then the timing of the printing mechanism must be adjusted so that the actual printing of the respective matter on the envelope will not begin immediately when the envelope to be printed reaches the printing wheel, but instead is delayed for a time until the envelope has advanced with its front edge beyond the printing wheel and presents a part of its surface at a distance rearwardly from the front edge thereof.

Such adjustment of the printing mechanism is accomplished by circumferentially turning the supporting disk 88 relative to the printing mechanism so that the impression of the latter is delayed sometime after the envelope has engaged the trip finger 96 and released the printing wheel and the envelope has passed a sufficient distance beyond the type face of this wheel.

Various means may be provided for thus adjusting the timing or control mechanism and the printing wheel circumferentially relative to each other, but it is preferable to employ for this purpose the means which are shown in Figures 6, 7 and 9 and include a set screw 108 which works in a threaded opening in the upper end of the printing wheel on one side of its axis and passes through a segmental slot 109 formed in the supporting disk 88 and bears with its head against the upper side of this disk. Upon loosening this set screw the supporting disk 88 may be turned circumferentially relative to the printing wheel either backwardly or forwardly for the purpose of either advancing or retarding engagement of the trip finger by the front edge of the letter to be marked, and after such adjustment the set screw is tightened to hold the control mechanism in the desired position relative to the printing wheel. It will be apparent that by setting the trip finger ahead the actual printing of the respective letter will be effected some time after the front edge of the letter has released the printing mechanism. It will now be apparent that the adjustment of the printing mechanism

can be so timed that the impression is thrown either forwardly or backwardly relative to the release of the printing wheel and thus permit of making the impression on the letters immediately adjacent to the front edge thereof or this impression may be made on the central part of the letters and thus suit the requirements of the particular matter which is being handled.

Between the separating roll 61 and the printing wheel a guide roll 110 is arranged which engages with the adjacent part of the front side of the longitudinal stretch 47 of the feed belt or the front side of the letter 24 which is being fed forwardly and thereby increases the gripping effect of the belt on the letters to insure proper movement of the same from the supply stack to the printing mechanism. This guide roll is pivotally mounted in the upper end of a pin 111 which has its lower part extending through the feed table 26 and is secured to frame plate 20 by a set screw 112, as shown in Figure 4, or other suitable means.

In rear of the longitudinal stretch 47 of the feed belt, backing means are arranged which operate to press this part of the belt laterally toward the guide roll 110 and the printing mechanism which backing means embody the present invention and are constructed as follows:

The numeral 113 represents a main backing roller which engages with the back or rear side of the operative stretch 47 of the feed belt transversely in line with the printing and driving wheels, and 114 represents a rear auxiliary backing roll which engages with the rear side of the respective stretch of the said belt transversely in line with the guide roll 110. The main backing roll 113 turns on the upper end of a vertical pivot pin 115 which extends downwardly through a segmental slot 116 in the feed table and the frame plate and is secured at its lower end to a supporting arm 117 which is pivoted by means of a pin 118 on the under side of this plate. The rear auxiliary backing roll 114 turns on a vertical pin 119 which is mounted on the rear part of a horizontally swinging yoke 120 which latter has its front part mounted on the pin 115 so as to be capable of turning thereon. This yoke together with the main and rear auxiliary backing rolls 113, 114, is constantly pressed toward the back side of the respective stretch of the feed belt by spring means which preferably consist of a helical spring 121 bearing at its inner end against the outer side of the yoke 120 while its opposite end bears against an adjusting screw 122 working in the upper end of a stationary post 123 mounted on the adjacent part of the frame, as best shown in Figures 1 and 5.

When a letter moves from the supply stack toward and past the printing wheel the respective part of the feed belt is deflected laterally in accordance with the thickness of the letter and during such deflection both the main and rear auxiliary backing rolls are moved to a corresponding extent in a direction away from the path of the letter which is being fed, this movement being resisted by the spring 121. As the letter leaves the supply stack it first passes between the guide roller 110 and that part of the feed belt which is supported by the rear backing roll 114, whereby the rear part of the yoke 120 is deflected and caused to rock on the front pivot pin 115 and as the letter progresses forwardly, the same passes between the printing wheel and the main backing roll 113, whereby the front part of the yoke is also moved laterally. During this last mentioned

11

movement the spring 121 causes the front and rear backing rolls to both bear with the same pressure against the back of the adjacent part of the feed belt and thereby produce a uniform feeding action of this belt regardless of the thickness of the letter which is being fed. By thus mounting the main and rear feed rolls on the same yoke and pressing the latter toward the path of the letters by a single spring device, the feeding belt is not only capable of yielding the requisite extent to adapt itself to letters of different thickness but it is also capable of accommodating itself to successive letters which vary in thickness and still produce a uniform gripping action of the feed belt against the same. If desired, an additional front auxiliary backing roll 124 may be employed, as shown in Figures 15 and 16, and pivoted by means of a pin 125 on the yoke 120 in front of the main backing roll 113 so as to bear against the back of the feed belt at a distance in front of the printing wheel. When marking letters or the like which are comparatively thin the use of the main backing roll 113 and the rear auxiliary backing roll 114 will usually suffice to support the feed belt and hold the same in position when the run of letters in a batch is relatively short, but when the letters in a batch which are being marked are of comparatively long length it is preferable to employ a front auxiliary backing roll 124, in addition to the main backing and rear auxiliary roll in order to obtain the desired gripping effect of the belt on the letters and insure proper feeding of the same past the printing mechanism.

By mounting a plurality of backing rolls on the same yoke or hanger as a unit it is possible to handle thicker letters and also handle mixed thick and thin letters with equal facility without liability of binding or choking the machine.

Various means may be employed for inking the type or impression surface of the printing wheel but it is preferable to employ for this purpose the improved mechanism which is shown in the drawings and which is constructed as follows:

The numeral 126 represents an ink delivery wheel or roll of fibrous, porous or absorbent material which engage with the periphery of the printing wheel on the side thereof opposite to where the latter engages with the letters which are to be marked. This inking wheel is provided with a metallic hub 127 which rotates on a pivot pin 128 mounted on the inner arm 129 of an adjusting lever pivoted by means of a pin 130 on the upper side of the feed table. This adjusting lever is yieldingly turned in the direction which engages the inking roll with the periphery of the printing wheel by means of a spring 131 engaging the outer arm 132 of the adjusting lever while its opposite end engages with a post 133 mounted on the adjacent part of the feed table. The pressure of the inking roll against the printing wheel may be regulated by means of an adjusting screw 134 passing through the outer arm 132 of the adjusting lever and the tension spring 131 and engaging its thread with an opening in the post 133 while its head bears against the outer side of the arm 132 of the adjusting lever, as shown in Figure 1. By turning the adjusting screw 134 in one direction or the other the tension of the spring 131 may be varied to secure the desired pressure of the ink roll against the periphery of the printing wheel.

Ink is automatically supplied to the ink delivery roll in accordance with this invention by means which include an annular reservoir or well

135, see Figs. 5 and 14, formed in the upper end of the hub 127 and adapted to hold a supply of liquid ink which is delivered therefrom to the ink delivery roller by means of one or more radial openings 136 extending from the bore of this well to the periphery of the hub 127. As the ink roller rotates, liquid ink is thrown by centrifugal force from within this well against the bore of the fibrous ink roller which latter is thereby saturated with ink and delivers the same from its periphery to the printing wheel.

The upper end of the ink well is normally closed by a disk shaped cover 137 which has its inner part connected with the central part of the hub 127 by means of a screw joint 138 while its marginal part bears against the upper end of the outer part of this hub and against the top of the ink roller 126, as shown in Figures 1 and 5. Replenishing of the well with ink may be effected through an opening 139 in the cover by any suitable means.

When preparing this inking device for use the inking wheel or roller 126 is first thoroughly loaded by rolling the same in ink and then removing the surplus and thereafter the same is automatically supplied with fresh ink from the well as the inking roll and well rotate.

As the letters are successively pushed laterally away from the front side of the front section 29 of the longitudinal guide wall the same are caused to stack in an upright position by restacking means which include the following:

The numeral 140 represents an upright restacking follower having the form of a plate arranged lengthwise over the front part of the table opposite the front section 29 of the longitudinal guide wall and provided at its rear end with a laterally bent lip or flange 141 whereby the letters, as they move forwardly from the printing mechanism to the restacking mechanism, are directed into the space between the restacking follower and this front guide wall section. This restacking follower is pivoted on the rear end of a supporting arm 142 by a pin 143, the front end of this arm being secured to the upper end of a shaft 144 which is journaled in a bearing on the front part of the frame. The restacking follower is constantly pressed toward the front guide wall section 29 by means which preferably comprise a spring 145 arranged below the front end of the feed table and connected at one end with an arm 146 on the lower end of the shaft 144, an adjusting screw 147 passing through an opening in the adjacent flange of the frame and connected at its inner end with the opposite end of the spring 145, and a screw nut 148 applied to the outer end of this adjusting screw and bearing against the outer side of the frame flange, as shown in Figure 2. By tightening or loosening the screw nut 148 the tension of the spring 145 may be adjusted to suit the required pressure of the restacking follower against the stack of letters which are being piled on the receiving section of the feed table.

In order to yieldingly hold the restacking follower in a position parallel with the rear guide wall section 29, or substantially so, a spring 149 is interposed between the front part of the restacking follower and the supporting arm 142 and this spring is held in position by means of a guide rod 150 curved concentrically with a pivot 143 and extending through the spring 149 and secured at its inner end to the restacking follower, while its outer end passes through an opening in the supporting arm 142. Excessive tilting

of the restacking follower relative to its supporting arm is prevented by means of a stop 157 arranged on the rear end of the supporting arm 142 and adapted to be engaged by the outer side of the restacking follower in rear of the pivot pin 143.

When comparatively long letters are being marked in the machine the forward movement of the same on the receiving section 26 of the feed table is limited by means of a fixed front stop wall 151 projecting laterally from the front guide wall section 29 across the path of the letters. When the letters of a batch are comparatively short the forward movement of these letters is arrested at a distance from this front fixed stop by means of an intermediate or rear stop 152 which can be moved into and out of its operative position so that this marking machine may be used either on letters which are comparatively short as well as on letters which are relatively long. In its preferred form this intermediate stop has the form of a bar which has its inner end pivoted by means of a screw 153 on a lug 154 projecting laterally from the rear guide wall section 29. This intermediate stop is adapted to be turned vertically into an operative horizontal position across the path of the letters, as shown by full lines in Figures 1 and 3 or the same may be swung to one side of this path, as shown by dotted lines in Figure 1. When in its operative position this intermediate stop engages with a notch 155 in the guide wall section 29 and engages its underside with a stop 156 on the lower end of this notch, thus limiting a downward movement of this stop bar when the same reaches its horizontal operative position. When the stop bar engages with a notch 155 the same is held reliably in position for arresting the forward movement of the letters which engage the same and when this stop bar is swung to the opposite side of its pivot the same completely clears the path of the letters and does not obstruct the forward movement of the same toward the fixed front stop 151.

The several novel features of this invention when taken together provide a marking machine which is very efficient in operation and permits of marking or cancelling letters with ease and facility and the same is also very simple and durable in construction and not liable to get out of order so that servicing of the same for maintaining the machine in good working condition is reduced to a minimum.

I claim:

1. A machine for marking letters and like matter, comprising a rotary printing wheel adapted to impress the matter to be marked and having a longitudinal groove in its bore a rotary driving wheel upon which said printing wheel is mounted which has a central tubular hub engaging the bore of said printing wheel and a lower driving rim engaging the lower end of said printing wheel, and means for frictionally coupling said driving wheel and printing wheel including a friction block arranged in said groove and engaging its inner side with the hub of said driving wheel, a bow spring arranged in said groove and engaging said block, and an adjusting screw arranged on said printing wheel and engaging said spring.

2. A machine for marking letters and like matter, comprising a rotary printing wheel adapted to impress the matter to be marked and having a longitudinal groove in its bore a rotary driving wheel upon which said printing wheel is mounted which has a central tubular hub engag-

ing the bore of said printing wheel and a lower driving rim engaging the lower end of said printing wheel, and means for frictionally coupling said driving wheel and printing wheel including a friction block arranged in said groove and engaging its inner side with the hub of said driving wheel and provided at its opposite ends with notches, a bow spring arranged in said groove and engaging said block, an adjusting screw arranged on said printing wheel and engaging said spring and retaining pins arranged on said printing wheel and engaging with said notches at opposite ends of said block.

3. A machine for marking letters and like matter, comprising a rotary printing wheel adapted to impress the matter to be marked and having a longitudinal groove in its bore a rotary driving wheel upon which said printing wheel is mounted which has a central tubular hub engaging the bore of said printing wheel and a lower driving rim engaging the lower end of said printing wheel, and means for frictionally coupling said driving wheel and printing wheel including a friction block arranged in said groove and engaging its inner side with the hub of said driving wheel, and provided at its opposite ends with outwardly opening notches and inwardly facing undercut shoulders, guide pins mounted on the printing wheel and projecting into said notches, an outwardly bowed leaf spring engaging its opposite ends with said shoulders, and an adjusting screw arranged on said printing wheel and engaging said leaf spring.

4. A machine for marking letters and the like, comprising a printing wheel for marking letters, means for moving the letters to be marked past said printing wheel including a propelling belt engaging one side of said letters, a driving wheel upon which said printing wheel is mounted and which is provided at its lower end with a driving rim adapted to be driven by the lower part of the belt, means for frictionally coupling said printing wheel and driving wheel, a supporting disk adjustable circumferentially on the upper end of said printing wheel and having a rim adapted to be driven by the upper part of said belt, and means for controlling the rotation of said printing wheel with said driving wheel including a trip lever pivoted on said disk and provided with a movable stop adapted to engage a fixed stop, and a trip finger pivoted on the trip lever and adapted to be engaged by the letters moved to said printing wheel.

5. A machine for marking letters and the like, comprising a printing wheel for marking letters, means for moving the letters to be marked past said printing wheel including a propelling belt engaging one side of said letters, a driving wheel upon which said printing wheel is mounted and which is provided at its lower end with a driving rim adapted to be driven by the lower part of the belt, means for frictionally coupling said printing wheel and driving wheel, a supporting disk adjustable circumferentially on the upper end of said printing wheel and having a rim adapted to be driven by the upper part of said belt, and means for controlling the rotations of said printing wheel with said driving wheel including a trip lever pivoted on said disk and provided with a movable stop adapted to engage a fixed stop, a trip finger pivoted on the trip lever and adapted to be engaged by the letters moved to said printing wheel, a stationary upright arbor about which said printing wheel, driving wheel and supporting disk turn, and means frictionally

15

connecting said driving and printing wheels including a friction collar mounted on said arbor, means for preventing turning of said collar on the arbor but permitting the collar to slide vertically on the arbor including a key pin passing through said collar and a vertical slot in said arbor, a spring arranged within said arbor and bearing at one end against said key pin, and an adjusting screw mounted on said arbor and engaging with said spring.

6. A machine for marking letters and the like, comprising means for propelling the letters to be marked and engaging one side of the same, printing means for marking the letters including a printing wheel adapted to engage the opposite side of the letters, controlling means whereby said printing wheel is held at rest preparatory to impressing a letter and which is operated by the forward movement of a letter to release the printing wheel and cause the latter to impress the letter, and means for adjusting the timing of the control mechanism relative to the operation of the printing wheel, said control mechanism including a supporting disk adjustable circumferentially relative to said printing wheel, means for holding said printing wheel and disk in different circumferential positions relative to each other comprising an adjustable screw secured to said printing wheel and passing through a segmental slot in said disk, a trip lever pivoted on said disk and having a movable stop adapted to engage a stationary stop, a spring for turning

16

said lever and yieldingly holding the movable stop thereon in engagement with said stationary stop, a trip finger pivoted on said trip lever and adapted to be engaged by the letters to be marked for releasing the printing wheel and starting of the same, and a spring for yieldingly holding the trip finger in the path of the letters to be marked.
